CLAIM

(21) Appl. No.: **29/156,243**

The ornamental design for a reservoir for a subcutaneous infusion set, as shown and described.

(22) Filed: **Feb. 26, 2002**

DESCRIPTION

(51) LOC (7) Cl. **24-01**

FIG. 1 is a front perspective view showing a reservoir for a subcutaneous infusion set embodying our new design;

(52) U.S. Cl. **D24/108**; D24/111; D24/130

FIG. 2 is a front elevational view thereof;

(58) Field of Search **D24/108, 111,**

FIG. 3 is a rear elevation view thereof;

D24/112, 114, 130; 128/DIG. 1, DIG. 12,

FIG. 4 is a left side elevation view thereof;

905; 604/218, 68, 110, 230, 141, 151, 70,

FIG. 5 is a right side elevation view thereof;

131, 155, 152, 154, 157, 187

FIG. 6 is a top plan view thereof;

4,969,874 A * 11/1990 Michel et al. 604/141

FIG. 7 is a bottom plan view thereof; and,

4,978,335 A * 12/1990 Arthur, III 128/DIG. 1

FIG. 8 is a rear perspective view thereof.
